(57) **CLAIM**

The ornamental design for a contoured masking patch, as shown and described.

DESCRIPTION

FIG. 1 is a top front perspective view of a contoured masking patch showing my new design;
FIG. 2 is a top rear perspective view thereof;
FIG. 3 is a front elevation view thereof;
FIG. 4 is a rear elevation view thereof;
FIG. 5 is a right elevation view thereof, with the left elevation view being a mirror image thereof;
FIG. 6 is a top elevation view thereof;
FIG. 7 is a bottom elevation view of the embodiment; and,
FIG. 8 is a section view of the invention, taken along 8-8 in FIG. 3.

The stippling shown in the drawings illustrate an adhesive surface of the contoured masking patch.
